UNITED STATES PATENT OFFICE.

CORNELIUS BENNETT HARNESS, OF LONDON, ENGLAND.

INHALER.

SPECIFICATION forming part of Letters Patent No. 311,314, dated January 27, 1885.

Application filed October 21, 1884. (No model.) Patented in England July 23, 1884, No. 10,500.

To all whom it may concern:

Be it known that I, CORNELIUS BENNETT HARNESS, electrician, a subject of the Queen of Great Britain, residing at London, England, 5 have invented an improved apparatus for facilitating the inhalation of medicated vapor for strengthening, enriching, and extending the range of the human voice, and for the treatment of pulmonary and other affections, 10 (for which I have obtained a patent in Great Britain, No. 10,500, bearing date July 23, 1884,) of which the following is a specification.

My invention relates to an improved apparatus for facilitating the inhalation of medicated vapor for strengthening, enriching, and extending the range of the human voice, and for the treatment of pulmonary and other affections. Its chief object is to provide means for enabling the person using the apparatus 20 to regulate or control the supply or admission of air to the same in a very convenient, simple, and efficient manner.

My improved apparatus is illustrated in the accompanying drawing, which shows the same 25 partly in elevation and partly in longitudinal central section.

a is a tube, which may be of block-tin or other suitable metal or material, and which is provided with a mouth-piece, *b*, midway between its ends. A ferrule or ring, *c*, having 30 an internal screw-thread, is soldered or otherwise fixed in each end of the tube *a*.

d are handles of wood or other suitable material, each provided with an externally-threaded piece, *e*, which fits into one of 35 the rings or ferrules *c*, so that the said handles may be screwed to the tube or unscrewed therefrom at will.

Through each of the handles *d* is passed a 40 rod, *f*, one end of which extends through the piece *e* and carries a plate or disk, *f'*. This plate or disk is provided on its inner face with a washer, *g*, of leather, india-rubber, or other suitable material, so as to form a valve capable 45 of closing the orifice or passage *e'* in the piece *e*. A spiral spring, *h*, is placed upon each of the rods *f*, so that it bears at one end upon the end of a recess or cavity, *d'*, in the handle, and at the other end upon a cap or push-piece, *f''*, 50 fixed on the outer end of the said rod. This

spring tends to press the washer *g* against the end of the piece *e*, and thus close the orifice or passage *e'*, thereby preventing the admission of air to the tube *a* through the said orifice. The opening of the said valve is effected by 55 pressing upon the cap or push-piece *f''*, and thereby forcing the rod *f* inward against the action of the spring *h*. A small aperture, *i*, is formed in each of the handles *d*, for the admission of air to the tube *a* when the said valve 60 is opened. The mouth-piece *b* has a perforated screw-cap, *b'*. This cap is made somewhat larger in diameter than the other part of the said mouth-piece, so that the latter can be easily retained in the mouth; but the said mouth-piece may, if desired, be made in any other suitable manner.

By providing the ends of the tube *a* with the ferrules or rings *c*, I insure the tightness of the joints between the said tube and the handles 70 by forming a wider surface for the said joints than would otherwise exist. I prefer to insert a ring or washer of elastic material between the ends of the tube *a* and the handles *d*.

In preparing my improved apparatus for use 75 one of the handles *d* is removed from the tube *a*, and the substance or compound the vapor of which is to be inhaled is placed within the said tube, (which is preferably filled with sponge, cotton-wick, or other absorbent material.) The said handle is then screwed tightly 80 to the end of the tube and the apparatus is ready for use, the said tube being kept air-tight by the pressure of the valves upon their seats.

The person desiring to use the apparatus grasps the two handles *d* and applies his mouth to the mouth-piece *b*. Then by pressing one or both of the caps or push-pieces *f''* he opens the orifice or orifices *e'* for the admission of air 90 to the tube *a*. He can then conveniently inhale the vapor of the substance contained in the tube, and at the same time regulate or control the supply or admission of air to the said tube by pressing more or less upon the said caps or 95 push-pieces.

I do not confine myself to the particular form of construction shown in the drawing, as it is obvious that the same may be somewhat modified. For example, the rods for oper- 100

ating the valves are in some cases bent and arranged to project through the handles on one side thereof, where they are provided with suitable means for operating them.

5 What I claim is—

1. The combination, with the tube *a*, having the mouth-piece *b*, of the handles *d*, screwed into the same and provided with valves and means for operating them to regulate or control the supply or admission of air to the said tube, substantially as and for the purpose set forth.

2. The combination, with the tube *a*, having the mouth-piece *b*, and provided with the ferrules *c c*, secured in each end of said tube, of the handle *d*, screwed into said ferrules, and provided with valves and means for operating them, substantially as described.

3. The combination, with the tube *a*, having the mouth-piece *b*, of the tubular handles *d*, 20 screwed into the same, and having apertures *i*, the rods *f*, valves *f'*, caps or push-pieces *f''*, and the springs *h*, substantially as and for the purposes set forth.

In testimony whereof I have hereunto signed 25 my name in the presence of two subscribing witnesses.

CORNELIUS BENNETT HARNESS.
